Primary Examiner — Khawaja Anwar*Assistant Examiner* — Mojtaba Tehrani(74) *Attorney, Agent, or Firm* — Christensen, Fonder, Dardi & Herbert PLLC(57) **CLAIM**

The ornamental design for a rifle cartridge, as shown and described.

DESCRIPTION

FIG. 1 is a front side view of the rifle cartridge. The rear side view, the right side view, and the left side view being identical thereto. The features as shown continue around the rifle cartridge; and,

FIG. 2 is a perspective view of the rifle cartridge. The bottom view is omitted and features thereon form no part of the claimed design.
